PAPER BAG

Roy W. Jaite, Lakewood, Ohio

Application May 29, 1931. Serial No. 541,017

1 Claim. (Cl. 229—62)

My invention relates to paper bags, and is an improvement pertaining more particularly to paper bags in which the opposite ends are closed, such for example, as in the so-called valve type in which the body of the bag is composed of a multiple or plural number of flat tubes or tubular plies of paper, and provided with a self-closing valve in one angular corner. Such bags are usually plicated or formed with pleated folds at their longitudinal edges, and closed at both ends, except for the valve opening in one corner. To close such ends the general practice is to sew the corresponding ends of the plies of paper together, and also to paste a binding strip around the end edges. Each tubular ply of paper also possesses a pasted longitudinal overlapping seam, the ends of which are traversed by the stitches and united together and to other overlapping plies in sewing operations. All the seams are located in the same side or in the same side wall of the bag and though the seam in each successive tube is usually placed in laterally offset relation to the seams in the other tubes it follows that the bag is not of uniform thickness across each end where stitched or sewed on a straight line transversely of the bag. That is, the sewed stitches which extend across the bag ends pass through successive areas of different thickness, inasmuch as each tube in the bag is of double thickness where seamed and only of single thickness elsewhere, excepting at the valve folds. In that connection be it known that the sewing needle passes through the thicker and thinner areas successively and punctures the paper at close intervals, and that the tension in the threads and on the paper may vary owing to the unequal thickness of the bag along the sewed line.

For practical usages, paper bags of the described type are of substantial size, say approximately fifteen inches wide and twenty-six inches long in the flat. They are used extensively for transportation of powdered materials, for example, cement, and hold about ninety-four pounds net. To carry that weight these bags must be made of relatively tough paper and embody a sufficient number of tubular plies to protect the goods therein and withstand breakage and rupture, especially when the bags are being filled, and when picked up and handled. Owing to frequent breakage, and loss of contents of such bags, the trade at present demands that such bags shall embody at least five tubular plies of paper of given quality and strength. However, different paper and a lesser number of plies of paper would suffice to make an acceptable bag, provid-

ing the bag would not tear or burst open especially in the region of the seams at opposite ends thereof. My object in general is to provide a bag made of the same or a lesser number of plies than as used and required heretofore, which will be stronger and more secure, and overcome the known dangers and objections in leakage, breakage, and rupture in that type of bag. A further object is to provide a bag in which the ends are more rigidly united in sealing union without sewing and without traversing or perforating by stitching, that is, a bag in which each ply resists with its entire cross section breakage and rupture, all as hereinafter more fully described and pointed out in the appended claim.

In the accompanying drawings, Fig. 1 is a side elevation, and Fig. 2 an edge view, on a reduced scale, of a paper bag embodying my invention. Figs. 3 and 4 are enlarged sectional views on lines 3—3 and 4—4 of Fig. 1, showing the interlocking of and sealing of the opposite walls at one end of the bag. Fig. 5 and Fig. 6 are obverse and reverse views of the same bag on a smaller scale, portions of the successive tubular plies being broken away in stepped relation to show the internal construction within the opposite sides of the bag. Figs. 7, 8, and 9, are diagrammatic views, corresponding to cross sectional views on lines 7—7, 8—8, and 9—9, of Figs. 4 and 5, respectively. Fig. 10 is a fragmentary perspective view of a sectional portion of the bag showing the sealing joint thereof.

As a preliminary, it should be understood that in manufacturing multi-ply bags of the kind disclosed in the drawings, a series of sheets or strips of paper are fed through a tubing machine and creased or folded to form a multi-ply tube A having pleats or inwardly extending folds 2 in the longitudinal edge portions thereof. The sheets are fed into the machine in superposed relation with their parallel edges offset or in stepped relation so that when the sheets are jointly folded to produce a flat plicated tubular body the parallel edge portions of each sheet will overlap and form longitudinal seams 3. Paste is also applied to the paper along the edge thereof so that the overlapping parts of the seam in each sheet are united together. The tubular products thus embody a multiple number of seamed tubes, sleeved together with the pasted seams 3 in the respective tubes extending longitudinally in parallel relation or side by side, all the seams being on the same side, that is, in the same side wall of the multi-ply tube. When the tubular product is severed into given lengths one plicated corner

thereof is folded inwardly to provide a valve 5 in the form of an open pocket or filling opening 5', the inturned walls of which extend a given distance inwardly on lines substantially parallel 5 with the transverse end edge of the sleeved tubes. While severing the tubular product in short tubes of given length, the opposite ends 6 of such tubes are simultaneously slit, preferably on converging lines 7, to form a number of tongues 8, which 10 thereafter are alternately folded in opposite directions and back upon the opposite walls of the tubes and pasted thereto. A folding of adjoining tongues in opposite directions and pasting of these tongues to opposite walls of the tube assures a tight, strong and sealing connection of these walls at their open ends. A wide binding strip 9 of paper or other material secured upon both sides of the outer tube by a paste or adhesive covers each seal entirely, re-enforces same 15 substantially and secures the tongues in their folded position.

As previously delineated all the seams of the bag are located on the same side or in the same side wall of the bag, so that one wall is substantially 20 re-enforced and thicker, even though the seams are placed in laterally offset position. Any breakage of the bag will therefore of course occur in the wall which is not re-enforced by the overlapping layers of a seam. To avoid such breakage and assure equal strength of both walls of the bag one or more re-enforcing strips 10 of paper or other material are placed lengthwise upon or within the plain unseamed wall of the sleeved tubes. The length of the re-enforcing strip 10, 25 only one of which is used in the three-ply bag shown in Figs. 5 through 8, corresponds to the length of the tubes so that the opposite ends thereof will be connected to and sealed with the

corresponding ends of all the tubes. The width of strip 10 is more or less optional, but is preferably chosen to correspond with the total width of all three seams. The benefits and advantages of such an arrangement are made manifest as 80 the body of the bag thus formed possesses the same or substantially the same resistance to tensile strains or stresses on both sides.

In manufacturing such bags the strip or strips 10 may be fed together with the several sheets of paper through the tubing machine, and the paste applied and the several sheets or plies folded and severed concurrently with the strip or strips to provide a re-enforced multi-ply tubular body of the requisite length from which to make a bag. 85 The tucking of the valve and the sealing operations of the open ends of the bag may be performed subsequently in another machine or in separate machines.

What I claim, is:

A paper bag, comprising a multiple number of seamed tubes, sleeved together with their pasted seams longitudinally arranged on the same side of the bag, a re-enforcement strip of paper extending longitudinally upon the plain unseamed 100 wall of the bag to the opposite ends thereof, a plurality of tapered locking tongues formed by slitting the opposite ends of said tube and said re-enforcement strip on converging lines, said tongues being folded alternately back upon the 105 opposite walls of said bag, and a binder strip pasted to and encircling the edge of said bag and covering said tongues, said tongues being of small width so that a plurality of said locking tongues extend over said re-enforcing strip to 110 securely interlock said strip with the opposite ends of said bag.
